UNITED STATES PATENT OFFICE.

WILLIAM T. WILKINSON, OF MEDFORD, MASSACHUSETTS.

TROLLEY-WHEEL.

SPECIFICATION forming part of Letters Patent No. 769,854, dated September 13, 1904.

Application filed December 18, 1903. Serial No. 185,644. (No model.)

To all whom it may concern:

Be it known that I, WILLIAM T. WILKINSON, a citizen of the United States, and a resident of Medford, in the county of Middlesex and State 5 of Massachusetts, have invented an Improvement in Trolley-Wheels, of which the following description, in connection with the accompanying drawings, is a specification, like figures on the drawings representing like parts.

10 The trolley-wheels for electric cars which are now in common use are cast in one piece of some material having good conductivity—such, for instance, as brass. The portion of the wheel which is subjected to the greatest 15 wear is that with which the conductor-wire contacts, the wear being such that the ordinary life of a trolley-wheel is only a few days. Where the wheel is cast in one piece, the entire wheel has to be thrown away when the 20 groove therein becomes worn to such an extent as to make it unfit for further use. This construction entails considerable expense, especially where the wheels are made of brass or other expensive metals. To overcome this, 25 it has been proposed to construct a trolley-wheel with a renewable center with which the wire contacts and which is detachably supported between flanges at the sides of the wheel, the idea being that the wear would occur 30 largely on the renewal of the center, which could be renewed when worn without necessitating the discarding of the entire wheel.

So far as I am aware in all previous attempts to construct a trolley-wheel with a renewable 35 center either said center has had in its periphery only a portion of the wire-receiving groove of the trolley-wheel and the side walls of the groove have been formed of some metal or material different from the center and which 40 is not intended to be renewable or the cheek-piece or flanges between which the renewable center has been held have not been shaped to fit the outside of the renewable center, and thus support the latter at all points.

45 In the first construction above mentioned the side walls of the groove become so worn after a short time that when a fresh center is placed between them the sides of the groove in said fresh center do not tally or register 50 with the sides of the groove as defined by the

worn flanges, and the result is that more or less arcing occurs, a proceeding which is always destructive to the trolley-wheel. In the other construction of wheel the outer faces of the renewable center are not supported throughout their entire extent, but only at those points where the cheek-pieces contact therewith, with the result that the center after having become only slightly worn is very apt to break down at its unsupported points. In order to overcome these disadvantages and at the same time to provide a trolley-wheel which is the equivalent in every way of a solid wheel, and yet which has a renewable center, I have designed the 55 wheel illustrated in the accompanying drawings, in which the renewable center has formed entirely therein the wire-receiving groove and is supported between cheek-pieces shaped to give proper support to the side faces of the center throughout their entire extent. 60

A trolley-wheel constructed as above described is the full equivalent in every way of a solid trolley-wheel and at the same time the worn parts can be renewed when necessary at a minimum expense. 65

70 In the drawings, Figure 1 is a side view of my improved wheel. Fig. 2 is a section on the line $\alpha\alpha$, Fig. 1.

The wheel comprises the two flanges or cheek-pieces 3 and 4, between which is the renewable center 5, which will preferably be of brass or other similar material having good conductivity. The cheek-pieces 3 and 4 may be detachably secured together in any suitable way, and, as herein shown, the cheek-piece 3 80 has integral therewith the hub 6, which is screw-threaded onto the hub 7 on the cheek-piece 4. The center 5 is of peculiar shape, it having the main or body portion 8 and the two flanges 9, which form between them the wire- 85 receiving groove of the trolley-wheel. Said flanges 9, which form the side walls of the groove, extend beyond the cheek-pieces 3 and 4 and overlap the latter at their peripheries, 90 as shown at 10. The center 5, therefore, is so shaped as to protect every portion of the cheek-pieces 3 and 4 from contact with the conductor-wire, the result being that the wire can only have contact with some portion of 95 said center. 100

It will be noted that the outside edges 11 of the portions 10 stand slightly beyond the outside of the cheek-pieces 3 and 4, so that even when the trolley-wheel jumps the wire these 5 projecting portions 10 prevent the wire from contacting with the cheek-pieces. The inner face 14 of each cheek-piece is shaped to fit the corresponding outer face of the center 5, so that the inner face of each cheek-piece contacts with and furnishes a support for the adjacent outer face of the center throughout its 10 entire extent. This I regard as quite an important feature of my invention, because thereby every portion of the center is firmly supported by one or both of the cheek-pieces, and the wheel when constructed is in every way 15 as solid as if it were cast solid, and there is no danger that the center 5 will break down until it has become completely worn out.

20 In a trolley-wheel constructed as above described the entire surface which is exposed to contact with the wire is of the same material and is part of the center, so that all of the wear comes on a single portion which can be 25 renewed easily and at a minimum expense when too worn for further use, and in addition the center is properly supported, so that it will not give way after slight use.

25 The hubs 6 and 7 of the cheek-pieces have 30 the central bore 12 therethrough, in which a suitable bushing (not shown) may be inserted to form a bearing for the pivotal pin on the trolley-pole or in which suitable roller-bearings may be placed, as desired.

35 The advantage of the roller-bearings over the bushing would be that they would wear very much longer than the bushings would.

While I have illustrated one specific form 40 of my invention, I do not wish to be limited thereto, as the shape of the parts may be varied and still embody the inventive idea, which is to so construct the center 5 that the wire-receiving groove is formed entirely therein.

Having described my invention, what I claim as new, and desire to secure by Letters 45 Patent, is—

1. A trolley-wheel having two cheek-pieces detachably secured together, and a renewable center confined between said cheek-pieces, said center having formed entirely therein the 50 wire-receiving groove of the wheel, and the inner faces of the cheek-pieces having a shape to contact with and support the outer faces of said center throughout their entire extent.

2. A trolley-wheel, having two cheek-pieces 55 detachably secured together, and a renewable center confined between said cheek-pieces, the inner face of each cheek-piece contacting with and supporting the adjacent outer face of the center throughout its entire extent and said center having in its periphery the wire-receiving groove of the wheel, the portions of the center forming the side walls of the groove extending beyond and overlapping the periphery of the cheek-pieces.

60 3. A trolley-wheel comprising two cheek-pieces each provided with an inwardly-projecting apertured hub, one of said hubs being screw-threaded to the other, and a renewable center encircling said hubs and confined between the cheek-pieces, the inner face of each cheek-piece contacting with and giving support to the adjacent outer face of the center throughout its entire extent and said center having in its periphery the wire-receiving 65 groove of the wheel, the portions of the center forming the side walls of said groove extending beyond and overlapping the periphery of the cheek-pieces.

70 In testimony whereof I have signed my name 80 to this specification in the presence of two subscribing witnesses.

W. T. WILKINSON.
